UNITED STATES PATENT OFFICE

WILLIAM E. WATT, OF EVANSTON, ILLINOIS

VENTILATING SYSTEM

Application filed February 26, 1926. Serial No. 90,765.

This invention relates to ventilating systems and mechanism thereof, and the principal object of the invention is the provision of new and improved means for supplying 5 fresh air to buildings and removing the foul air therefrom without the aid of fans or other devices for artificially circulating the air.

Another object of the invention is the provision of new and improved means for utilizing 10 an air conduit either for admitting fresh air to the building or for providing for the escape of foul air therefrom, depending on the direction of the wind.

A further object of the invention is the provision of a new and improved ventilating system that will supply fresh air to a building with a minimum amount of inconvenience to the occupants of the building, and that is so constructed that the air that escapes is the 20 foulest in the room.

A still further object of the invention is the provision of a ventilating system and mechanism therefor that is simple in construction, easily assembled and installed, cheap to 25 manufacture, efficient in operation, and that is not likely to become damaged or get out of order.

Other and further objects and advantages of the invention will appear from the following description taken in connection with the 30 accompanying drawings, in which

Fig. 1 is a vertical section of a building showing one form of the invention in position therein;

Fig. 2 is a vertical section of a portion of a 35 wall of a building, showing the air chamber and vertical and auxiliary conduits in section;

Fig. 3 is a vertical section of a portion of 40 one of the auxiliary conduits showing a valve in position therein;

Fig. 4 is a vertical section of a portion of 45 an auxiliary conduit showing one of the ports;

Fig. 5 is a vertical section of a portion of a 50 building showing a modified form of the ventilating system in position therein;

Fig. 6 is a similar view showing a further 55 modified form of ventilating system;

Fig. 7 is a vertical section of a portion of 60

a building through one of the windows and showing a still further modified form of ventilator in position therein; and

Fig. 8 is a front elevation thereof.

On the drawing the reference character 4 55 designates a building in which one embodiment of the invention is installed. For the purpose of illustration, the building is shown as comprising three stories 5, 6 and 7, each divided into a number of rooms having ceilings 60 or top walls 8, 9 and 10 respectively, as is usual in such constructions. Each room may, if desired, be provided with a ventilating system comprising a two-way duct for supplying fresh air to the building and for removing the foul air therefrom. As shown, the system comprises a main conduit 11 secured in the wall 12 of the building, preferably on the side from which the prevailing winds blow, and also one in the opposite wall 13. A 70 pair of these conduits is employed for each tier of rooms. The conduits 11 may be formed in the wall during their construction or they may be provided as a separate or additional construction. In any event, they extend vertically and their upper ends are in communication with the outside atmosphere. Since these conduits are alike only one need be described.

As shown in Fig. 2, an opening is made in 80 the wall and a chamber 14 is provided therein. The chamber 14 is provided on its outer side with louvers for permitting the entrance of air into said chamber and for preventing the entrance of rain, snow, and the like. The 85 chamber 14 is in communication with a passage 11 in the wall which extends downwardly in said wall to a point immediately below the ceiling of the lowermost room. Preferably, though not necessarily, there are a pair of 90 these conduits for each vertical tier of rooms arranged one in one side wall of the building and the other in the opposite side wall thereof.

In order to deliver fresh air to the room or remove foul air therefrom, laterally extending branch or auxiliary conduits leading from the main conduit are provided. As shown, in Figs. 1 and 2 these auxiliary conduits 15, 16 and 17 extend from one side 95 of the building 4 to the other adjacent to 100

the ceilings 8, 9 and 10 respectively, and have their ends in communication with the vertical conduits 11 in the walls 12. Each of the conduits 15, 16 and 17 is provided in each room with one or more openings or ports 18 through which air may pass into or out of the rooms from the conduits 11 or into the same.

Since the interiors of buildings requiring ventilation are usually warmer than the outside air, as in factories, foundries and in all dwellings, stores and the like in cool weather, the outside air will be heavier and will flow down the conduits 11 and out through the auxiliary conduits into the rooms. The auxiliary conduits are preferably arranged adjacent to the ceilings of the rooms and the ports 18 are preferably on the upper side of the auxiliary conduits. These ports may be and preferably are openings formed in the auxiliary conduits.

The cross-sectional area of the conduits 11 at their upper ends are each equal to the combined cross-sectional area of the auxiliary conduits, and decreases downwardly so that at any point in the conduit the cross-sectional area thereof will be equal to the combined cross-sectional area of the auxiliary conduits below that point, as clearly indicated in Fig. 1 of the drawings.

On the lee side of the building or the side opposite which the wind is blowing, there is usually more or less suction, and this will tend to cause a reverse current to flow outward from the building through said conduits. Since the foulest air is usually warm air it rises, and by locating the ventilator conduits adjacent to the ceiling this foul air readily escapes through the conduits to the exterior of the building.

It has been found by experiment that the movement of the air through the ventilating conduits alternates first one way, then the other. At one time the fresh air may be entering, and at another time the foul air being leaving the building through that same conduit.

Where the auxiliary conduits extend entirely across the building as shown in Fig. 1, these conduits may be, and preferably are, provided with gates or valves 21, see Fig. 3, which are adapted to be closed so as to divide each conduit into two independent passages whereby fresh air may enter at one end while foul air is discharged at the other, or fresh air may be entering from both ends simultaneously, and vice versa.

In the operation of the device, air may enter one or both of the main conduits and from there pass into the rooms through the auxiliary conduits, or the heated air in the rooms may be conducted through the auxiliary and main conduits into the atmosphere. In reality, the auxiliary and main conduits may be considered two-way ducts for re-

moving foul air and for supplying fresh air to the building. Under certain conditions, as in perfectly calm weather, a stream of fresh air may be entering while one of heated or foul air may be leaving the room through the auxiliary conduit if the same be of fairly good size. On windy days the air may be flowing first one way and then the other in the conduits due to the fluctuations of the wind. For instance, on windy days, it is known that the velocity of the wind may vary from zero to its maximum velocity at that time, and consequently at the instant of maximum velocity air may be entering the building on the windward side due to the pressure exerted by the moving mass, and when it drops to its minimum pressure air in the building will escape through the conduits thereby materially changing the air in the building.

In Fig. 5 is shown a slightly different system. In this construction, the main conduits 11 are substantially the same as those just described. The auxiliary conduits 22 however do not extend entirely across the building and their ends are left open whereby air may enter or be discharged therethrough.

In order not to detract from the appearance of the room it is often desirable to conceal the auxiliary as well as the main conduits. In this event, the auxiliary conduits 23 are concealed in or formed in the ceilings of the building. The discharge openings or ports 24 are on the lower sides of the pipes and are preferably provided with a suitable grating for partially concealing the same. By means of this arrangement objectionable drafts are eliminated while fresh air is being supplied to the room.

In Figs. 7 and 8 is shown a modified form of construction, in which the system is in the form of an attachment that may be applied to the ordinary window. As shown, a chamber 26 is secured on the inside of the window 27 adjacent to the top thereof. The chamber 26 extends entirely across the window and has its outer side open or provided with louvers 28 for admitting air. The upper sash 29 of the window is adapted to form a closure for the chamber 26. In other words, by lowering the sash 29 the size of the opening leading to the chamber 26 may be regulated. One or more ventilating conduits 31 are secured to the chamber 26 and extend inwardly therefrom adjacent to the ceiling 32. The conduit 31 is provided with one or more ports or openings 33 through which air passes into and out of the room. By making the conduit 31 fairly large the same will act as a two-way duct for supplying fresh air to the room and for removing the foul air therefrom.

If desired a valve 35 may be placed in each conduit 31 for controlling the passage of air therethrough, whereby the window sash may

remain in lowered position or the panes opposite the chamber removed.

In some cases, instead of attaching the chamber 26 to the upper portion of a window frame and using the window sash as a valve, 5 the chamber may be attached over any opening through the wall, the passage of air through the conduit or conduits 31 being controlled by the valve 35.

10 It is thought from the foregoing taken in connection with the accompanying drawings that the construction and operation of my device will be apparent to those skilled in the art, and that various changes in size, 15 shape, proportion and details of construction may be made without departing from the spirit and scope of the appended claims.

I claim as my invention:

1. In a ventilating system for buildings 20 having a plurality of stories, said system comprising a vertical passage having its cross-sectional area reduced at each story in its descent, a comparatively large conduit extending laterally from said passage at each 25 story, the cross-sectional area of the upper end portion of said passage being as great as the combined cross-sectional area of said conduits.

2. In a ventilating system for a multi- 30 story building, a vertical passage in one of the walls of said building, said passage being provided with a port adjacent its upper end for the passage of air from the atmosphere into and from said passage, conduits extending 35 laterally from said passage and having ports adjacent the ceilings of the rooms of each story for discharging air delivered thereto by gravity from said passage into said rooms, and for removing the heated vitiated air from the upper portion of each 40 room.

In testimony whereof I affix my signature.
WILLIAM E. WATT.
